CLAIM

The ornamental design for a solar mosquito repellent lamp, as shown and described.

DESCRIPTION

FIG. 1 is a front, top perspective view of a solar mosquito repellent lamp, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the area labeled **9** in FIG. 1; and,

FIG. 10 is an enlarged view of the area labeled **10** in FIG. 2.

The broken lines show portions of the solar mosquito repellent lamp that form no part of the claimed design.

The dashed lines in the figures illustrate portions of the solar mosquito repellent lamp that form no part of the claimed design.

The dash-dot broken lines represent stitching that forms no part of the claimed design.

The dot-dash-dot broken lines of the solar mosquito repellent lamp in FIG. 1 illustrate a boundary and cut line of the enlarged view in FIG. 9 and form no part of the claimed design.

The dot-dash-dot broken lines of the solar mosquito repellent lamp in FIG. 2 illustrate a boundary and cut line of the enlarged view in FIG. 10 and form no part of the claimed design.

1 Claim, 10 Drawing Sheets
